United States Patent Office

Des. 211,981
Patented Aug. 20, 1968

211,981

UTILITY CART

David L. Kelley, Novelty, Ohio, assignor to Du-Fold, Inc.

Filed June 9, 1966, Ser. No. 2,630

Term of patent 14 years

(Cl. D14—3)

Fig. 2

Fig. 3

I claim:

The ornamental design for a utility cart, as shown.
